UNITED STATES PATENT OFFICE

172,324

BAR FOR TRAFFIC CENTER LINE

Grant A. Wiswell, Burlingame, Calif., assignor to
Wiswell Safety Centerline, Inc., San Francisco,
Calif., a corporation of California

Application December 9, 1953, Serial No. 27,998

Term of patent 14 years

(Cl. D72—1)

To all whom it may concern:

Be it known that I, Grant A. Wiswell, a citizen of the United States and a resident of Burlingame, California, have invented a new, original, and ornamental Design for Bar for Traffic Center Line, of which the following is a specification, reference being had to the accompanying drawing forming a part hereof.

Fig. 1 is a top plan view of a bar for traffic center line, showing my new design.

Fig. 2 is a side elevational view thereof.

Fig. 3 is a bottom plan view thereof.

Fig. 4 is an end elevational view thereof looking at the left end of Fig. 1.

Fig. 5 is an end elevational view thereof looking at the right end of Fig. 1.

Fig. 6 is a sectional view taken along the line 6—6 in Fig. 1.

Fig. 7 is a sectional view taken along the line 7—7 in Fig. 2.

I claim:

The ornamental design for a bar for traffic center line, substantially as shown.
